FLOATING TYPE MANDREL FOR TUBE DRAWING

Filed Dec. 24, 1943

UNITED STATES PATENT OFFICE

2,359,339

FLOATING TYPE MANDREL FOR TUBE
DRAWINGCarl H. Wadell, Fairfield, Conn., assignor to
Bridgeport Brass Company, Bridgeport, Conn.,
a corporation of Connecticut

Application December 24, 1943, Serial No. 515,588

14 Claims. (Cl. 205—7)

This invention relates to improvements in tube drawing apparatus, and more particularly to a floating mandrel plug and shank construction for use in connection with conventional draw-bench constructions and drawing dies. In my co-pending application Serial No. 479,425, filed March 17, 1943, of which this application is a continuation in part, a construction has been described that is useful for tube drawing operations.

It is an object of the present invention to provide an improved form of such construction that is useful especially in the drawing of heavy gauge tubings or in reduction operations that require a long bearing die or any reduction operation that would allow metal to work in behind the tungsten carbide shell. In such operations it is necessary to provide means to prevent the tube from working in behind the sizing mandrel or sleeve because such an occurrence will result in breakage of the said mandrel or sleeve or in the bending of its supporting stud, and, consequently, result in waste and in loss of time. In addition sizing mandrels or sleeves are comparatively costly and breakage is expensive. It is another object of the invention to provide means that will eliminate the difficulties just discussed.

A further object of this invention is to provide a novel mandrel shank to be utilized with the sizing mandrel or sleeve whereby the latter will be less subject to breakage or damage when used particularly in the drawing of heavy gauge tubings or in reduction operations that require a long bearing die or any reduction operation that would allow metal to work in behind the tungsten carbide shell.

To the accomplishment of the foregoing and such other objects as may hereinafter appear, the invention consists in the novel construction and arrangement of parts hereinafter described and then sought to be defined in the appended claims, reference being had to the accompanying drawing forming a part hereof, which shows, merely for the purposes of illustrative disclosure, a preferred embodiment of the invention, it being expressly understood, however, that various changes may be made in practice within the scope of the claims without digressing from the inventive idea.

In the drawing, in which similar reference characters denote corresponding parts:

Fig. 1 is a longitudinal sectional elevation of a portion of a draw bench construction, its die and tubing being drawn, and shows the mandrel construction in position of use therewith;

Fig. 2 is a section taken along line 2—2 of Fig. 1 viewed in the direction of the arrows;

Fig. 3 is a section taken along line 3—3 of Fig. 1, also viewed in the direction of the arrows;

Fig. 4 is an end view of the mandrel construction viewed from the right of Fig. 1;

Fig. 5 is a longitudinal section taken along line 5—5 of Fig. 1 viewed in the direction of the arrows and showing relative displacement of the sizing mandrel on its retaining stud; and

Fig. 6 is an elevational view of a modified form of retaining stud that may be used with the device.

Referring to the drawing 10 denotes tubing and 11 denotes a die through which the tubing is to be drawn in any well known manner.

15 A floating plug or mandrel construction 13 is placed within the die and tubing 10. This construction 13 comprises a mandrel shank 14. This shank has a portion 15 of enlarged diameter at one end. The enlarged portion 15 is provided with an enlarged countersunk or bore portion 16 to form a forwardly extending annular skirt portion 17 for a purpose to be presently described.

20 A bored or countersunk portion 18 of reduced diameter extends axially adjacent to the portion 16. A threaded bored portion 19 of reduced diameter extends axially as a continuation of the portion 18. An unthreaded portion 20 of further reduced diameter extends axially as a continuation of the portion 19 and the portion 20 connects with a bored portion 21 of still further reduced diameter in the body of the shank. The rear end of the shank 14 is provided with an axially extending threaded bored portion 22. The latter communicates with the bored portion 21 by a bored portion 23 of reduced diameter. The bored portions 16, 18, 19, 20, 21, 22 and 23 are all in axial alignment and in effect constitute a continuous bore through the shank having differing diameters in various portions thereof as indicated.

25 A milled flat 24 for the use of a wrench may be provided in the shank 14. 25 and 26 are oil holes drilled at desired angle to bore 21 to provide lubrication supplied through hollow plug rod 27. The shank 14 is adapted to be screwed onto the plug rod 27. This plug rod 27 is supported in well known manner (not shown) during the drawing operation, for example in the manner described in my aforesaid application.

30 35 40 45 50 55 A retaining stud 28 is formed with a threaded portion 29 which is adapted to threadedly engage in the threaded portion 19 of the shank. This stud has a reduced end portion 30 adapted

A retaining stud 28 is formed with a threaded portion 29 which is adapted to threadedly engage in the threaded portion 19 of the shank. This stud has a reduced end portion 30 adapted

to fit within the portion 20 of the shank and an unthreaded portion 31 that extends outwardly of the shank. A head 32 is provided on the end of the outwardly extending portion 31. This head has an annular abutment flange 33 and a rounded portion 34 of reduced diameter which may be provided with flattened sides 35 to permit application of a tightening tool or the like. The overall diameter of the flange 33 is less than the maximum outside diameter of the shank 14.

The retaining stud 28 carries a loosely fitting sizing mandrel or sleeve 36. This sleeve 36 is substantially shorter than the portion 31 of the stud. Its outside diameter is substantially less than the inside diameter of the skirt portion 17 and its length furthermore is admeasured so that when its forward end lies in abutment with the flange 33, the skirt 17 overlaps its rearward end for a purpose to be presently described. The internal diameter of the sleeve or mandrel 36 is substantially greater than the diameter of the portion 31 of the stud so that said sleeve or mandrel 36 may be moved or shifted laterally as well as longitudinally with respect to the stud axis. The diameter of the bore 16 forming the skirt portion 17 is made large enough so that the skirt portion will not interfere with lateral displacement of said sleeve or mandrel 36. The outer wall 36a of the sleeve may be tapered if desired. The leading peripheral edge 36b of the sleeve 36 is tapered preferably with a 45 degree taper while its rearward or trailing peripheral edge 36c is rounded or tapered to any desired angle.

A suitable coil spring 37 is carried on the stud 28. This spring is adapted to be received in the bored portion 18 of the shank 14. This spring is in compressed condition and abuts the shoulder 18a of the bore 18 and the rearward or trailing end of the sleeve 36. The spring 37 serves to urge the sleeve 36 into abutment with the flange 33. The greatest shock to which the mandrel sleeve 36 is subject occurs when the tube 10 leaves said sleeve. The spring 37, however, also acts as a shock absorber at that time and eliminates the hazard of sleeve breakage at such time.

Preferably flange 33 has a smaller diameter than the diameter of the forward end of sleeve 36.

An alternative form of retaining stud may be used with the shank 14 in place of stud 28. Such a stud 40 is shown in Fig. 6. This stud 40 has a threaded portion 41 adapted to threadedly engage the threaded portion 19 of the shank. This stud 40 also has a reduced portion 42 adapted to fit within the bore 20 of the shank and portions 43 and 44 forwardly of the threaded portion 41 of successively smaller diameters. The portion 43 is adapted to receive the spring 37 and the portion 44 is admeasured to receive the mandrel or sleeve 36. As with the stud 28, the portion 44 has a substantially smaller diameter than the internal diameter of the sleeve or mandrel 36, so that the same lateral and longitudinal displacements of the sleeve or mandrel 36 may take place. A head 45 is provided on the outer end of the portion 44. This head has an abutment flange 46 and a head portion 47 similar in form and purpose to the corresponding parts 32 and 33 on the stud 28. It also has flattened sides 48 similar in purpose to sides 35. The overall outside diameter of the flange 47 is preferably less than the diameter of the leading end of the sleeve 36.

Either the stud 28 or the stud 40 may be used with the shank 14. The stud 40 has some ad-

vantages in that it is lighter while being provided with necessary strength at those places most subject to strain during use in tube drawing and allows standardization of thread diameters.

5 During the draw, imperfections on the inside surface of the tube, and lack of uniformity of tube thickness are compensated for by the lateral displaceability of the mandrel sleeve 36 with respect either to the stud 28 or 40. Thus in Fig. 10, 15, the sleeve 36 is shown displaced from concentricity with respect to the axis of stud 28 to substantially the limit permitted by the differences in diameter between the portion 31 of the stud 28 and the internal diameter of the sleeve 36, a condition resulting from abnormally thick tubing wall on one side of the sleeve 36. Normally the sleeve 36 is self-centering, being positioned as shown in Fig. 1 when uniform wall thickness is encountered during the draw. The displaceability of the sleeve is of great importance as it eliminates breakage that would occur with a rigidly positioned mandrel, encountering tube conditions tending to produce the position of the sleeve 36 shown in Fig. 5.

25 Moreover, the skirt portion 17 overlaps the rear end of the sleeve 36 at all times so that it is impossible for the material of the tube 10 at any time to work in behind the rearward end of the sleeve 36 and interfere with the functioning of 30 the spring 37. This is very important especially when the sleeve is of cemented tungsten carbide "Carboloy." "Carboloy" is a material rather weak in tensile strength and also weak in resisting shock. The spring 37 overcomes these drawbacks. During the time when the tube 10 is being drawn the entire assembly comprising the rod 27 and appendages are under severe tensile stress. As soon as the tube 10 leaves the die 11 these stresses are released very suddenly. When 40 this release occurs, the sleeve would set up a compressive stress between the sleeve and the shank 14 that would be likely to damage the sleeve. In the embodiment shown, when release occurs, the spring 37 absorbs the shock which in constructions embodying other forms of constraining members have resulted in injury to the sleeve. Such shock absorption prevents injury to the sleeve 36 and renders practicable the use of "Carboloy" sleeves. If any tube metal could work itself in behind the sleeve, the action of the spring might be hampered. Thus the presence of skirt 45 17 eliminates such danger and renders the device practicable under all tube drawing conditions.

Another great advantage of the novel construction is that the same shank and stud can be utilized to mount replaceably several different sizes of mandrels or sleeves 36.

55 For example, with a stud diameter in portions 31 or 44 of .437 inch, mandrel sleeves each having an inside diameter large enough to permit floating action and respectively any outside diameter that allows sufficient shell wall strength and clearance with respect to the skirt portion 17 may be used. Other sizes, too, are contemplated.

60 Another important advantage is that the mandrel construction described results in great economy. This is so because mandrel sleeves can be replaced on the same mandrel shank without any machining or fitting thereby making it unnecessary to provide separate mandrel shanks for each mandrel sleeve. The savings are in the order of twenty dollars per shank.

65 Economy also results from the fact that damage to the mandrel sleeve 36 adjacent either of

its ends does not require that the sleeve be discarded. It may be trimmed off to eliminate the damaged portions. In such event, the spring 31 may be replaced by a longer spring to compensate for the shortened sleeve length or the use of a shorter stud allows the same spring to be used. Since these sleeve mandrels are very expensive, the savings are material and apparent.

In the embodiment described, the studs 28 and 40 are preferably of heat-treated tool steel, the shank can be of any commercial tool steel that may be heat-treated while the sleeve mandrel is of cemented tungsten carbide, one commercially available material therefor being "Carboloy."

While specific construction details have been described, and specific dimensional characteristics mentioned as well as specific materials, it is to be understood that variations in structure, dimensions and materials are contemplated within the scope of the claims. There is no intention of limitation to the exact details described.

What is claimed is:

1. A tube drawing mandrel construction comprising a mandrel shank, a stud threadedly engaging said shank, a sizing mandrel or sleeve removably carried on said stud, said mandrel or sleeve having a larger internal diameter than the external diameter of said stud, and said mandrel or sleeve being shorter than said stud whereby said mandrel or sleeve may be displaced longitudinally and laterally on said stud, a retaining head on said stud, spring means on said stud for urging said mandrel or sleeve into abutment with said head, and a skirt portion extending from said shank, said skirt portion having a larger internal diameter than the outer diameter of said mandrel or sleeve and being admeasured to overhang the rearward end of said mandrel or sleeve whereby to prevent the tube being drawn from working in behind said mandrel or sleeve.

2. A tube drawing mandrel construction comprising a mandrel shank having a threaded axially extending bore, a concentrically arranged skirt portion at one end of said shank, a stud threadedly engaging in said bore and extending outwardly of said skirt portion, a headed portion on said stud adjacent its outermost end, a sizing mandrel or sleeve removably carried on said stud, said mandrel or sleeve having a larger internal diameter than the external diameter of said stud, being of shorter length than said stud and having a smaller external diameter than the internal diameter of said skirt portion whereby said mandrel or sleeve may be displaced longitudinally and laterally on said stud, and spring means on said stud for urging said mandrel or sleeve into abutment with said head, and said skirt portion being admeasured to overhang the rearward portion of said mandrel or sleeve when the latter is in abutment with said head whereby to prevent tubing being drawn from working in behind said mandrel or sleeve.

3. A tube drawing mandrel construction comprising a mandrel shank having a threaded axially extending bore, a concentrically arranged skirt portion at one end of said shank, a stud threadedly engaging in said bore and extending outwardly of said skirt portion, a headed portion on said stud adjacent its outermost end, a sizing mandrel or sleeve removably carried on said stud, said mandrel or sleeve having a larger internal diameter than the external diameter of said stud, being of shorter length than said stud and having a smaller external diameter than the internal diameter of said skirt portion whereby said man-

drel or sleeve may be displaced longitudinally and laterally on said stud, and spring means on said stud for urging said mandrel or sleeve into abutment with said head, said skirt portion being admeasured to overhang the rearward portion of said mandrel or sleeve when the latter is in abutment with said head whereby to prevent tubing being drawn from working in behind said mandrel or sleeve and said shank and stud being of tool steel and said mandrel or sleeve being of cemented tungsten carbide.

4. A tube drawing mandrel construction comprising a mandrel shank, said shank having an enlarged skirt portion at one end, a stud positioned in said shank and extending outwardly of said skirt portion, a sizing mandrel or sleeve removably carried on said stud, said mandrel or sleeve being shorter than said stud, having a larger internal diameter than said stud and having a smaller external diameter than said skirt portion whereby said mandrel or sleeve may be displaced longitudinally and laterally on said stud, and spring means carried on said stud for urging said mandrel or sleeve away from said shank, and said skirt portion being admeasured to overhang the rearward portion of said mandrel or sleeve when the latter is in its outermost position relative to said shank, whereby to prevent tubing being drawn from working in behind said mandrel or sleeve.

5. A tube drawing mandrel construction comprising a mandrel shank, said shank having an enlarged skirt portion at one end, a stud positioned in said shank and extending outwardly of said skirt portion, a sizing mandrel or sleeve removably carried on said stud, said mandrel or sleeve being shorter than said stud, having a larger internal diameter than said stud and having a smaller external diameter than said skirt portion whereby said mandrel or sleeve may be displaced longitudinally and laterally on said stud, and spring means carried on said stud for urging said mandrel or sleeve away from said shank, and said skirt portion being admeasured to overhang the rearward portion of said mandrel or sleeve when the latter is in its outermost position relative to said shank, whereby to prevent tubing being drawn from working in behind said mandrel or sleeve, said shank and said stud being of tool steel and said mandrel or sleeve being of cemented tungsten carbide.

6. A tube drawing mandrel construction comprising a mandrel shank, said shank having an enlarged skirt portion at one end, a stud positioned in said shank and extending outwardly of said skirt portion, a sizing mandrel or sleeve removably carried on said stud, said mandrel or sleeve being shorter than said stud, having a larger internal diameter than said stud and having a smaller external diameter than said skirt portion whereby said mandrel or sleeve may be displaced longitudinally and laterally on said stud, and spring means carried on said stud for urging said mandrel or sleeve away from said shank, said spring also serving as a shock absorber for said mandrel or sleeve when tubing being drawn leaves said sleeve, and said skirt portion being admeasured to overhang the rearward portion of said mandrel or sleeve when the latter is in its outermost position relative to said shank, whereby to prevent tubing being drawn from working in behind said mandrel or sleeve.

7. A tube drawing mandrel construction comprising a mandrel shank, said shank having an enlarged skirt portion at one end, a stud posi-

tioned in said shank and having a uniformly diametered portion extending outwardly of said shank and of said skirt portion, a sizing mandrel or sleeve removably carried on said stud, said mandrel or sleeve being shorter than said stud, having a larger internal diameter than said stud and having a smaller external diameter than said skirt portion whereby said mandrel or sleeve may be displaced longitudinally and laterally on said stud, and spring means carried on said stud for urging said mandrel or sleeve away from said shank, and said skirt portion being admeasured to overhang the rearward portion of said mandrel or sleeve when the latter is in its outermost position relative to said shank, whereby to prevent tubing being drawn from working in behind said mandrel or sleeve.

8. A tube drawing mandrel construction comprising a mandrel shank, a stud positioned in said shank, said stud having portions of successively different diameters extending outwardly from said shank, said shank having an enlarged skirt portion and said stud extending outwardly of said skirt portion, a sizing mandrel or sleeve removably carried on the outermost of said portions of said stud, said mandrel or sleeve being shorter than said last-named portion of said stud and having a larger internal diameter than said last-named portion, and having a smaller external diameter than said skirt portion of said shank, whereby said mandrel or sleeve may be displaced both longitudinally and laterally on said stud, and spring means carried on said stud for urging said mandrel or sleeve away from said shank and serving also as a shock absorber for said mandrel or sleeve, and said skirt portion of said shank being admeasured to overhang the rearward portion of said mandrel or sleeve when the latter is in its outermost position relative to said shank whereby to prevent tubing being drawn from working in behind said mandrel or sleeve.

9. A tube drawing mandrel construction comprising a mandrel shank having a threaded axially extending bore, a countersunk portion of different diameter adjacent the outer end of said threaded portion, and a second countersunk portion of still different diameter adjacent said first-named countersunk portion, said second-named countersunk portion defining a skirt portion for said shank, a stud threadedly engaging said threaded portion of said shank and extending outwardly of said skirt portion, a headed portion on said stud adjacent its outermost end, a sizing mandrel or sleeve carried on said stud, said mandrel or sleeve being shorter than said stud, having a larger internal diameter than said stud, and having a smaller external diameter than said skirt portion, whereby said mandrel or sleeve may be displaced longitudinally and laterally on said stud, and spring means on said stud for urging said mandrel or sleeve towards said head and for action as a shock absorber, and said skirt portion being admeasured to overhang the rearward portion of said mandrel or sleeve when the latter is in abutment with said head whereby to prevent tubing being drawn from working in behind said mandrel or sleeve.

10. A tube drawing mandrel construction comprising a mandrel shank, said shank having an enlarged skirt portion at one end, a stud positioned in said shank and extending outwardly of said skirt portion, a tapered sizing mandrel or sleeve removably carried on said stud, said mandrel or sleeve being shorter than said stud,

having a larger internal diameter than said stud and having a smaller external diameter than said skirt portion whereby said mandrel or sleeve may be displaced longitudinally and laterally on said stud, and spring means carried on said stud for urging said mandrel or sleeve away from said shank, and said skirt portion being admeasured to overhang the rearward portion of said mandrel or sleeve when the latter is in its outermost position relative to said shank, whereby to prevent tubing being drawn from working in behind said mandrel or sleeve.

11. A tube drawing mandrel construction comprising a mandrel shank having a threaded axially extending bore, a countersunk portion of different diameter adjacent the outer end of said threaded portion, and a second countersunk portion of still different diameter adjacent said first-named countersunk portion, said second-named countersunk portion defining a skirt portion for said shank, a stud threadedly engaging said threaded portion of said shank and extending outwardly of said skirt portion, a headed portion on said stud adjacent its outermost end, a sizing mandrel or sleeve carried on said stud, said mandrel or sleeve being tapered and having a rounded or tapered peripheral rear edge and additionally tapered forward peripheral edge, and said mandrel or sleeve being shorter than said stud, having a larger internal diameter than said stud, and having a smaller external diameter than said skirt portion, whereby said mandrel or sleeve may be displaced longitudinally and laterally on said stud, and spring means on said stud for urging said mandrel or sleeve towards said head and for action as a shock absorber, and said skirt portion being admeasured to overhang the rearward portion of said mandrel or sleeve when the latter is in abutment with said head whereby to prevent tubing being drawn from working in behind said mandrel or sleeve.

12. A tube drawing mandrel construction comprising a mandrel shank, a retaining stud extending from an end of said shank, a sizing mandrel or sleeve removably carried on said stud, said mandrel or sleeve having a larger internal diameter than the external diameter of said stud, and said mandrel or sleeve being shorter than said stud, whereby said mandrel or sleeve may be displaced longitudinally and laterally on said stud, spring means carried on said stud serving as a shock absorber for said mandrel or sleeve, and a skirt portion extending from said shank and admeasured to overhang the rearward end of said mandrel or sleeve whereby to prevent tubing being drawn from working in behind said mandrel or sleeve.

13. A tube drawing mandrel construction comprising a mandrel shank, a retaining stud extending from an end of said shank, a sizing mandrel or sleeve removably carried on said stud, said mandrel or sleeve having a larger internal diameter than the external diameter of said stud, and said mandrel or sleeve being shorter than said stud, whereby said mandrel or sleeve may be displaced longitudinally and laterally on said stud, spring means carried on said stud serving as a shock absorber for said mandrel or sleeve, and a skirt portion extending from said shank and admeasured to overhang the rearward end of said mandrel or sleeve whereby to prevent tubing being drawn from working in behind said mandrel or sleeve.

14. A tube drawing mandrel construction com-

prising a mandrel shank, a retaining stud extending from an end of said shank, a sizing mandrel or sleeve removably carried on said stud, said mandrel or sleeve having a larger internal diameter than the external diameter of said stud, and said mandrel or sleeve being shorter than said stud, whereby said mandrel or sleeve may be displaced longitudinally and laterally on said stud, spring means carried on said stud serving as a shock absorber for said mandrel or sleeve, 10

and a skirt portion extending from said shank and admeasured to overhang the rearward end of said mandrel or sleeve whereby to prevent tubing being drawn from working in behind said mandrel or sleeve, and threaded means in conjunction with the other end of said shank for attachment of the latter to a restraining member or plug rod in tube drawing apparatus.

CARL H. WADELL.
